BURNER NOZZLE AND CONTROL MEANS

Charles V. Moore, Austin, Tex.

Application July 3, 1945, Serial No. 603,010

3 Claims. (Cl. 299—118)

1

It is an object of this invention to provide a novel burner nozzle including therein an automatic control means to control the amount of fuel passing through the exit of the nozzle. The control means is automatically operated by the pressure of the fuel within the nozzle barrel.

It is an object of this invention to provide a novel burner nozzle that may be readily substituted for conventional burner nozzles now in use to thereby provide an automatic control means completely housed within the nozzle construction.

It is also an object of this invention to provide a very simple, sturdy and reliable device that can be produced in quantity at a low cost.

Other objects of my invention will be revealed as a complete description of the embodiment disclosed herein and in the accompanying drawing is presented.

In the drawing:

Figure 1 is a longitudinal sectional view through the central portion thereof disclosing my new nozzle having the automatic control means within the nozzle.

Figure 2 is a transverse sectional view taken on the line 2—2 of Figure 1, looking in the direction indicated by the arrows.

Figure 3 is an elevational view of the disc as seen from the inside.

The reference characters used on the drawing and in the specification identify the essential structural parts, features and portions of the completed device.

In the single embodiment described herein and shown on the drawing, it is noted that a tubular member or barrel 1 defines a fuel chamber 2. The tubular member 1 is provided with a reduced portion 3 thereby providing a shoulder 4. The reduced portion 3 is provided externally with screw-threads 5, while internally it is beveled outwardly defining a bevel 6.

A nozzle body 7 is threadedly mounted on the threaded portion 3 and fits accurately against the shoulder 4. The body 7 is provided with a centrally located opening 8 defining a housing for a sliding element or valve 9 and also defining a bearing for the connected end portion of the valve stem 10 of said valve 9. The valve 9 is provided with a frusto-conical outer portion complementary to the contour of the apertured portion 15.

The body 7 is provided with exit apertures or bores 11 extending therethrough and into an annular channel 11'. Both the body 7 and the disc 14 are provided with straight grooved portions

5 defining outlet passages 12, 12', 12a, 12b arranged substantially tangentially to the tapered outlet portion of the orifice 15. These grooves 12, 12', etc., maintain communication between the annular channel 11' and the orifice 15.

The body 7 is provided with a flanged screw-threaded ring 13 securing the apertured disc or jet sprayer 14 in place on said body 7. The aperture 15 has a tapered wall and an outlet orifice for the fuel jet to be ignited and burned in the furnace. The opening 8 is in alignment with the orifice 15, whereby the valve 9, having a tapered or frusto-conical portion, may cooperate with the tapered wall of the aperture 15.

15 The body 7 is also provided with supporting members 16, 17, 18 extending into the barrel 1 and connected to a control unit 19 and supporting said unit substantially centrally within the barrel. The control unit 19 is completely immersed in the furnace fuel within the barrel 1.

The control unit 19 comprises a hollow cylinder 20 having a flexible corrugated diaphragm 21 secured on the cylinder by a flanged screw-threaded ring 22. The arms 16, 17, 18 are connected to 25 the ring 22 by any suitable means, the opposite end of the cylinder being provided with an adjustable screw-threaded cap 23. The cap 23 is provided with a tubular stud 24 centrally located within said cap and cylinder 20, said stud constituting a centering device for a helical compression spring 25. The stem 10 is provided with a spring abutment 26 against which the spring 25 presses and abuts. The stem 10 is provided with 30 threaded nuts 27 and 28 threaded on said stem in position to grip the central portion of the diaphragm 21. The spring abutment 26 is secured on the stem 10 in suitably spaced relation to the nut 28.

In the control unit 19 the compression spring 35 25 rests or presses on the inside of the adjustable cap 23. When it is desired to adjust the spring pressure to produce the desired results, it is necessary to remove the body 7 from the barrel 1 by unscrewing the body 7 on the threaded portion 3, 40 and since the body 7 having the supporting arms 16, 17, 18 is connected to the unit 19, the unit can readily be withdrawn from the barrel 1 for adjustment of the spring pressure. When the desired adjustment has been made, the body 7 and 45 barrel 1 are re-assembled which appears to be clearly obvious from the construction shown and described.

The specific embodiment shown on the drawing has now been partly described in detail, but 50 it is self-evident that many changes in details

could be made without discarding the essential elements or the salient features of the invention.

This invention is primarily intended as a substitute nozzle for other nozzles used in furnaces in a steam heating system having a control means or system for mixing the ingredients of the fuel plus a pressure control means involving the use of steam from the furnace or system to provide a suitable pressure for the fuel.

In the operation of my nozzle the fuel is contained in the chamber 2 and when the pressure increases, that pressure tends to reduce the volume of the unit 19 and as a consequence, the flexible diaphragm 21 is flexed inwardly into the unit 19 and in response to this movement the stem 10 and valve 9 are drawn along with the movement of the diaphragm to increase the amount of valve opening and thereby provides for a more free flow of the fuel.

This free flow retards the speed and force of flow and prevents the carrying of the flame an undue distance beyond the exit orifice 15 of the burner nozzle.

When the pressure is reduced in the chamber 2 by the free flow or otherwise, the diaphragm 21, the valve 9 and its stem 10 are propelled to normal position by the spring 25, whereby the exit passageway is reduced in size, thereby reducing the quantity of fuel flow and simultaneously increasing the speed of flow a sufficient amount to maintain the flame in proper position relative to both the furnace and the exit end of the nozzle. The capacity of the exit or sprayer jet orifice is controlled directly and proportionally to the pressure of the fuel within the barrel 1.

It is the function of the control unit 19 to maintain the flame in a substantially constant position within the furnace and in proper position relative to the exit portion of the nozzle.

The barrel 1 may be provided with means such as screw-threads, apertured flange, etc. (not shown), whereby the burner nozzle may be installed in new structures or substituted for other nozzles not having my novel control means or unit.

Having fully described my invention and the operation thereof, what I claim is:

1. In a burner nozzle, the substructure comprising a body in combination with an automatic control unit, said body having spaced arms extending therefrom in the same general direction and connected to the control unit, said body having exit bores for the fuel flow therethrough, said control means having a flexible diaphragm, said diaphragm being actuated in one direction by a compression spring and in the opposite direction by fuel pressure, in combination with a valve and its stem, said stem being connected to said diaphragm and adapted to be actuated thereby responsive to fuel pressure, said stem and valve be-

ing slidably associated with said body and said body defining a guide for said stem and valve, said body having grooves extending respectively from said bores to said valve.

5 2. In a burner nozzle, the substructure comprising an automatic control unit, said unit having a cylinder, cap members, a flexible diaphragm, a valve and its stem, a spring and arms to support said unit, said stem being connected to said diaphragm and said diaphragm being connected to said cylinder by one of said cap members, said stem having a shoulder located in said cylinder, the other cap member having adjustable screw-threaded connection with the other end of the cylinder, said last-named cap member having a hollow projection extending into the cylinder and defining both a centering means for a helical compression spring, said spring rests at one end upon the inside of the adjustable cap member while its opposite end rests against the shoulder of the valve stem.

3. A burner nozzle comprising a barrel, a body, a sprayer jet means, an automatic control unit, said body being detachably connected to said barrel in substantially axial alignment therewith, said body receiving a valve and its stem and forming a guide means for said valve and its stem, said body having supporting arms for said unit, said arms being connected to said body and to said unit whereby said unit is supported substantially centrally of said barrel, said sprayer jet means being detachably connected to said body in axial alignment therewith, said sprayer jet means having an exit orifice centrally located therein, said body having exit bores for the fuel and also having grooves defining channels providing communication between said bores and said orifice, said unit comprising a cylinder having a helical compression spring therein and screw-threaded cap members on its ends, a flexible diaphragm secured on one end of the cylinder by one of said screw cap members, said diaphragm being connected to said valve stem, said other cap member being adjustable and defining a rest for one end of said helical compression spring, said adjustable cap member having a hollow portion extending into the cylinder and forming a centering means for said spring, said stem having a shoulder in the cylinder, said shoulder comprising a stop engaging one end of the compression spring in a position remote from said adjustable cap member, said valve and stem being urged toward closing position by said spring, said valve and stem being urged in the opposite direction against the tension of said spring by the pressure of the fuel in said barrel thereby automatically controlling the flow of fuel through said exit orifice.

CHARLES V. MOORE.
